UNITED STATES PATENT OFFICE

2,550,298

STABLE MARINE VESSEL

Frederick B. Romero, Washington, D. C.

Application January 29, 1946, Serial No. 643,981

6 Claims. (Cl. 114—61)

1

The object of the invention is to reduce rolling and pitching of vessels on rough surfaced water, in heavy seas to prolong the period of rolling and pitching; thereby producing a more stable vessel which is smoother and steadier to ride. To this end the invention consists of the hull of a vessel having five keels one forward and four aft with three channels between the after keels and broad strengthening members extending across the after channels. A further object of the invention is generally to improve the construction of marine vessels' hulls of the type set forth. Other objects and advantages will be more apparent from the following description made in connection with the accompanying drawing wherein like reference characters refer to the same parts in the several views and in which:

Fig. 1, is a side elevation partially in section.
Fig. 2, is an end elevation of the stern.
Fig. 3, is a plan view of the upper deck.

The upper deck 1 is integrally attached to the side shell plating 2 and stern plating, attention is invited to Fig. 2, wherein the upper stern plates are indicated at 3.

As illustrated in Figs. 1 and 2 the bottom of the hull is recessed along the center line from a point forward of amidships and approximately half way to the bow, thence rearwardly to the stern to form a central water channel 6, the top of which is defined by plating 4, stiffened by stiffener 17, and the sides by plating 5. A forward central keel 18, extends from the forward end of this channel 6, to the bow of the vessel. Said forward keel 18, has its flat bottom shaped so that its lateral edges follow long curved and diverging lines from the lower end of the bow's stem rearwardly to the after end where channel 6, begins. The top 4 of channel 6 begins at the end of the channel keel 18 with a rounded upward curve then continues with a flat portion extending upwardly and toward the stern to a point adjacent the designed load water line there curves to a horizontal portion which lies substantially in the designed load water line plane, LWL in Fig. 2 and continues to the stern of the vessel. Keels 15, 16 designated side keels for reasons appearing here below, extend from the forward end of the channel 6, substantially to the stern of the vessel. These side keels 15, 16 are of appreciable thickness with vertical sides facing the channel 6 and forming continuations of the channel side plating 5. The outer sides of keels 15 are set at an angle to the inner side such that these keels are thicker where they join the hull than they are at their lower edges.

2

The sides 2 are extensive and forward of the forward end of the central channel 6 extend from the sides of the deck 1 to the central keel 18. Throughout the length of channel 6 the sides 2 of the vessel extend in a generally vertical plane from the sides of the deck 1 to the bottom of the vessel where they turn inward. 10 become tangent to a generally horizontal plane and then sweep inwardly and upwardly terminating at the outer faces of side keels 15, 16. This upward and inward sweep is of considerable proportion and forms with the outer faces of side keels 15, 16 V-shaped side channels designated 19, 20 in the drawing. Two bilge keels 12, 13 one along each turn of the bilge also extend approximately from a point in a transverse plane which includes the after end of the central keel 18 to the stern of the vessel, these keels are of lesser depth forward but curve to the 20 greater depth illustrated in Fig. 2.

As indicated on the drawing the central channel 6 ends adjacent the stern but sufficiently forward of the extreme end of the vessel to provide a widened channel of the same height as channel 6 and of sufficient length to accommodate the balanced rudder 7 and permit it to turn in the usual manner. The stock of the rudder 7 is supported above and below by supports 8 and 9 respectively.

The hull portions on each side of the central channel 6 are tied together and the hull strengthened by heavy flat bars 14 which extend from the bottom of the hull immediately adjacent the turns of the bilges across the V-shaped channels 19, 20 through the side keels 15, 16 and across the channel 6. The flat bars 14 are of appreciable width, are equally spaced and as illustrated in the drawing they lie in a plane immediately along the bottom of the hull. Upon reference to the drawing it is noted that there are 5 of these elements. Various changes in size of the different parts may be made within the scope of the appended claims which limit the shape of the different parts so as to require that the finished vessels' hulls appear, in their outside structural forms, as shown, in the illustrative drawings accompanying this specification.

The vessel may be made of steel, steel alloys or wood and may include decks as they prove necessary or desirable but these are not deemed essential to the invention, which is constructed according to principles in naval architecture which include stress analysis requirements for safety of human life and cargo at sea.

I, the inventor, am aware that the herewith disclosed marine vessel's hull is of such unique

shape in its structure when considered in its entirety, that it fulfills the requirements of patentability as set forth in R. S. 4886; 35 U. S. C. 31, under rule 47 of the Rules of Practice effective March 1, 1949, in the United States Patent Office: therefore,

I claim,

1. A vessel adapted to ride steadily in a heavy sea having a hull, said hull including sides and a bottom joining along a turn at the bilge at each side, the bottom formed to provide a plurality of keels and channels all extending longitudinally thereof, one of said keels lying along the longitudinal center line of the hull and extending from the bow to a point approximately half way to amidships and there terminating in a channel, said channel extending to the stern of the vessel and of a depth to extend up to the designed load water line, a pair of keels lying directly along each side of said channel and extending throughout the length thereof, a second pair of keels lying along the turn at the bilges also extending along the length of said central channel, and channels V-shaped in cross section along each side of the bottom each of the last mentioned channels lying between a keel at the bilge and a keel at the side of the central channel.

2. A vessel as claimed in claim 1 including a balanced rudder within the after end of said central channel.

3. A vessel as claimed in claim 1 including a

plurality of flat bars of appreciable width lying in a common plane and extending from adjacent each keel at the bilge across the V-shaped channels, the keels at the side of the central channel and across the central channel.

5. A vessel as claimed in claim 1 wherein the top of said central channel is flat and parallel to the bottom thereof substantially throughout the entire length of said channel.

6. A vessel as claimed in claim 1 wherein the sides of the keels along the central channel form continuations of the sides of said channel.

10 15

7. A vessel as claimed in claim 1 wherein the keels along side the central channel increase in thickness from the lower to the upper edges thereof.

FREDERICK B. ROMERO.
